PROJECTILE LIFT

This application is a national stage filing of International (PCT) Application No. PCT/EP2021/054009, corresponding to International Publication No. WO 2021/165387 filed on Feb. 18, 2021, which in turn claims priority to German Application No. 10 2020 104 466.6 filed on Feb. 20, 2020. The entire contents of both of those applications are hereby incorporated by reference.

The disclosure relates to a projectile lift for the vertical movement of ammunition bodies between two storage levels in a magazine having a receiving tray for receiving an ammunition body and a holding device for holding the ammunition body.

BACKGROUND

Particularly in military vehicles, there is often only a very small amount of space available for magazines for the storage of ammunition bodies, which is why the ammunition bodies are usually stored horizontally in the corresponding magazines one on top of the other in multiple storage levels. In order to introduce the projectiles, some of which are over 40 kg in weight, into the magazine, or to remove them from it again, the projectiles must be moved back and forth in a vertical direction between the storage levels.

On account of the heavy weight, this involves very high degree of physical exertion during a manual movement by hand. On this basis, projectile lifts can be used, with which the ammunition bodies can be automatically moved back and forth between the different storage levels.

The projectile lifts may have a receiving tray for receiving an ammunition body, onto which the ammunition bodies can be slid when ammunition is being added to the magazine. After this, the ammunition bodies can be moved into the corresponding storage level.

Furthermore, there may also be a holding device for holding the ammunition bodies. The holding device may be arranged on the side of the receiving tray, for example, and at least partially encompass the ammunition bodies to secure them, so that they can no longer move sideways and in a vertical direction. Problems result, however, if the ammunition bodies are to be ejected from the projectile lift sideways or introduced into the projectile lift sideways. Although the ammunition bodies can be pushed out of the receiving tray in the longitudinal direction when the securing is released, said securing may make it difficult for the ammunition bodies to be slid out sideways and therefore for the ammunition bodies to move between the storage levels.

On this basis, a problem addressed by the disclosure is that of specifying a projectile lift which allows a simple movement of the ammunition bodies between the different storage levels and also a corresponding method for the vertical movement of ammunition bodies.

SUMMARY

This problem can be solved in the case of a projectile lift of the kind referred to above, in that the holding device can raise an ammunition body vertically from the receiving tray.

By raising the ammunition body, it is not necessary to eject it laterally from the receiving tray, but the ammunition body can be displaced onto the receiving tray and then gripped by the holding device, for which purpose the holding device can be transferred from a gripping position to a retaining position. The holding device can then be lifted vertically together with the ammunition body and then

2

moved to a transfer position in which the ammunition body can be ejected from the holding device and fed to the corresponding storage level.

With regard to the receiving tray, it has proved to be advantageous if the ammunition bodies can be displaced on the receiving tray in the longitudinal direction. The receiving tray can be open at the front and rear ends, so that ammunition bodies can be displaced from behind onto the receiving tray and pushed forward out of the receiving tray. In this respect, the receiving tray can serve as a linear guide for the ammunition bodies so that they are retained securely in the receiving tray and cannot be pushed out of the side of the receiving tray. The receiving tray can be of a cylindrical segment form and the inner diameter of the receiving tray can be adapted to the largest diameter of the ammunition body. As a rule, this will be the diameter at the lower end of the ammunition body. This allows the ammunition bodies to be safely guided in the receiving tray. The longitudinal axis of the ammunition body, if it is lying on the receiving tray, corresponds to the longitudinal axis or the cylinder axis of the receiving tray.

The receiving tray can be longer than the ammunition bodies, so that they do not protrude from the receiving tray. The receiving tray may have substantially the same length as the holding device or as the retaining shells of the holding device.

It has also proved to be advantageous if the holding device and the receiving tray are arranged parallel to each other. This design ensures that an ammunition body located on the receiving tray can be reliably grabbed and lifted away by the holding device. The ammunition body does not have to be rotated or swiveled. At the same time, it is also ensured that the ammunition body can be placed on the receiving tray in order to be able to move, for example, into a removal position in which the ammunition body can be pushed out of the magazine. The holding device may have a rotation axis and the rotation axis may be parallel to the longitudinal axis of the receiving tray.

In a development, it is also proposed that the holding device can be moved relatively in respect of the receiving tray in the vertical direction. This design makes it possible that the distance of the holding device from the receiving tray is not constant, but the holding device can move towards the receiving tray, for example to pick up and lift an ammunition body from the receiving tray.

To this end, it is further proposed that the holding device can raise the ammunition bodies from the receiving tray in the manner of a grab and deposit them on the receiving tray. Due to the grabber-like design, the holding device can lift an ammunition body upwards out of or from the receiving tray and it is not necessary that the ammunition body can also be pushed onto the holding device. The actual movement of the ammunition bodies between the storage levels can thus be undertaken by the holding device and the receiving tray allows the ammunition bodies to be inserted into the projectile lift.

From a design viewpoint, it has proved to be advantageous if the receiving tray has a recess, in particular two recesses. One, in particular two, projectile supports may be provided, which may, for example, be arranged on the floor of the projectile lift or the magazine. If the receiving tray is located in the lowest storage level, the projectile support can extend through the recesses and hold part of the ammunition body. The design and position of the projectile support can be adapted to the contour of the ammunition body. This is because this is usually narrower in the front region than in the rear region, so that the projectile support can support the

ammunition body, especially in the front region. In this respect, the projectile support can also ensure that the holding device can reliably grab the ammunition bodies and then lift them from the receiving tray.

It has proved to be advantageous for movement of the holding device can be moved in the vertical direction via a linear drive. By means of the linear drive, the holding device can be moved up and down and moved to any storage level. The linear drive enables precise position control of the holding device, so that the ammunition bodies can be reliably lifted from or placed on the receiving tray and the various storage levels can be approached precisely.

Furthermore, it has proved to be advantageous if two linear drives are provided, wherein the one linear drive may be arranged on one side of the holding device and the other linear drive on the other side of the holding device. These two linear drives ensure that the holding device remains as straight as possible during a vertical movement, so that the ammunition body cannot move unintentionally due to an inclination. Furthermore, the weight of the ammunition body located in the holding device can be evenly distributed by two linear drives. It may be advantageous if one linear drive is arranged in one end region of the holding device and the other linear drive is arranged in the other end region. The holding device can then extend between the two linear drives.

With regard to the design of the linear drive, it has proved to be advantageous if this has at least one, in particular two, rotatable threaded spindles, which move the holding device in a vertical direction when rotated. Due to the use of a threaded spindle, the position of the holding device can be controlled very precisely. The movement of the holding device can be dependent on the direction of rotation of the threaded spindle, for example the retaining shell can be moved upwards when the threaded spindle is rotated clockwise, and downwards when the threaded spindle is rotated counterclockwise. Two threaded spindles allow the acting forces to be evenly distributed, which improves the overall stability of the projectile lift. It may be advantageous if the threaded spindles are arranged parallel to each other and extend perpendicular to the longitudinal axis of the ammunition body or perpendicular to the holding device. Furthermore, it may be advantageous if both linear drives each have two threaded spindles, so that the holding device can be moved up and down by four threaded spindles in total. This ensures particularly uniform support of the holding device.

The threaded spindles of a linear guide can be rotatably supported at the lower end in a bearing rail, so that they do not shift, but retain a firmly defined position even during a rotation. Also at the upper end of the threaded spindles, where the lifting motor and the gearing mechanism can be arranged, the two threaded spindles can be connected to each other via a corresponding bearing rail. The linear drive can then have a rectangular shape.

In a development, it is proposed that the linear drive has a guide element, which is arranged in the manner of a spindle nut on the threaded spindle. By rotating the threaded spindle, the guide element can be moved up and down. The guide element may be connected to the holding device, in particular the holding device is rotatably mounted in or on the guide element. The guide element can be arranged on both threaded spindles of a linear drive and can connect the two threaded spindles to each other in this respect. The guide element may have two threaded holes through which the two threaded spindles can extend, wherein the threads can mesh together in such a way that the guide element can be moved in a vertical direction. It may be advantageous if two guide

elements are provided, one for each linear drive. The holding device can then be rotatably supported on both sides in or on a guide element.

To turn the threaded spindle it has proved to be advantageous if a lifting motor is provided, which can drive the threaded spindle, in particular both threaded spindles of a linear drive, via a gearing mechanism. The lifting motor may be located at the upper end of the linear drive so that it does not obstruct the movement of the holding device. The lifting motor can be connected via a gearing mechanism to both threaded spindles of a linear drive, so that the two threaded spindles always rotate synchronously. This prevents the guide element from tilting due to uneven rotation of the threaded spindles. With two linear drives, a separate lifting motor may be provided for each linear drive. Both lifting motors can be coupled to each other, in particular via a corresponding controller, so that all four threaded spindles rotate synchronously.

According to an advantageous development, it is provided that the receiving tray can be moved in the vertical direction. By moving the receiving trays, ammunition bodies can be pushed onto the receiving tray at different levels and pushed out of the receiving tray at different levels. For example, it may be desirable to load ammunition in the ammunition depot at the lowest level and to remove the ammunition bodies at a higher level. The receiving tray can then be moved to the desired ammunition position and the ammunition bodies can then be lifted off the receiving tray by means of the holding device and then stored. If an ammunition body is to be removed from the magazine, it can be placed on the receiving tray by the holding device. In a next step, the receiving tray can then be moved to the removal position and the ammunition body can be pushed out at the desired location. The movement of the receiving tray thus allows variable loading of ammunition and removal of ammunition bodies at different levels. In this respect, the projectile lift can therefore also be used for existing magazines and vehicles and can also serve as a retrofit solution.

With regard to the relative movement of the receiving tray and the holding device, it has proved to be advantageous if the receiving tray and the holding device are coupled to one another in such a manner that the receiving tray can be moved along with the holding device when the holding device is located within or above a limit level. It may be advantageous if the limit level is the second storage level. The storage levels are counted from below, with the lowest level corresponding to the first level. If, for example, the holding device is moved upwards and exceeds the limit level, the receiving tray is moved accordingly. The holding device and the receiving tray are then coupled and they move simultaneously by the same distance in the vertical direction.

Furthermore, it has proved to be advantageous if the receiving tray is decoupled from the holding device when the holding device is below the limit level. In order to pick up an ammunition body from the receiving tray or to place an ammunition body from the holding device onto the receiving tray, both the receiving device and the holding device can be moved to the lowest storage level. To achieve this, the holding device below the limit level can be moved independently of the receiving tray. The receiving tray may be located at the lowest level if the holding device is at the limit level.

If the holding device is located at or above the limit level, the receiving tray may be located below the holding device by the distance of the limit level from the lowest level. If, accordingly, the second storage level is the limit level, the

distance of the receiving tray from the holding device is then the distance of the limit level from the lowest storage level.

From a design viewpoint, it may be advantageous if the receiving tray is coupled to the holding device via a linear guide. Due to the linear guide, the receiving tray can be moved vertically together with the retaining shell by means of the linear drive. The receiving tray does not require its own drive, but this is moved by means of the lifting motor or the lifting motors of the linear drives. The linear guide can be designed as a vertical strut that can extend parallel to the threaded spindle. It may be advantageous if two, in particular four, linear guides are provided so that the receiving tray can be safely moved in the vertical direction, even if an ammunition body is resting on it. Each two of the four linear guides can be connected to an end region of the receiving tray. Furthermore, it is possible that two linear guides are connected to each other, in particular via a U-shaped connection. Due to this design, the receiving tray can rest on the connection of the two linear guides, which increases stability. Furthermore, it may be advantageous if the linear guide is guided in the guide element.

In the case of a relative movement of the holding device in relation to the receiving tray, the guide element can slide over the linear guide so that the receiving tray is not moved with it.

In a development of the linear guide, it is proposed that this has a limit stop which limits a movement of the holding device in respect of the receiving tray. The stop can be arranged at the upper end of the linear guide and ensure that the guide element moves the mounting shell with it. In the case of a vertical movement upwards, the guide element can hit the stop, so that in the event of a further movement, the receiving tray is moved together with the guide element or the holding device. The stop can hit the guide element if the holding device is at the limit level.

The distance of the limit stop from the receiving tray or the length of the linear guide may be such that the distance between the receiving tray and the holding device corresponds to the distance of the lowest storage level from the limit level. If, for example, the second level is the limit level, the length of the linear guide can be such that the distance between the holding device and the receiving tray corresponds to a storage level.

Furthermore, it is proposed that the receiving tray is suspended from the holding device so as to be movable linearly. The receiving tray may be suspended from the holding device by means of the guide element. Although the linear guide may consist of rigid struts, these can basically act like ropes. This is because if the receiving trays have not yet reached the lowest storage level, the receiving tray can move in parallel with the holding device. If the holding device reaches the limit level and the receiving tray reaches the lowest storage level, the holding device can be moved further downwards and can then, lift an ammunition body from the receiving tray, for example.

With regard to the holding device, it has proved to be advantageous if it has two retaining shells, which are connected to each other at one end by a gearing mechanism and at the other end by a rotary bearing. The rotary bearing can be mounted in a guide element or the rotary bearing can be part of the guide element, so that the two retaining shells can be rotatable relative to the guide element. The opposite sides of the retaining shells can be mounted in another guide element, so that the holding device is then arranged between the two guide elements and is rotatable relative to them.

With regard to the holding device, it has proved to be advantageous if it can be moved into a retaining position, a

transfer position and a grabbing position. In the retaining position, an ammunition body can be secured in the holding device and moved in a vertical direction together with the holding device. In the grabbing position, the holding device can be moved from above to an ammunition body located on the receiving tray, so that the holding device grabs the ammunition body at least partly. If the holding device is then moved to the retaining position, the ammunition body is secured in the holding device and can then be lifted off the receiving tray. In the transfer position, an ammunition body can be ejected from the holding device, especially laterally, and then fed to a retaining place of a magazine, for example.

With regard to the problem mentioned at the beginning, a method for the vertical movement of ammunition bodies between two storage levels of a magazine is further proposed, wherein the magazine comprises a receiving tray for receiving an ammunition body and a holding device for holding the ammunition body, and wherein the holding device vertically raises an ammunition body from the receiving tray.

It has been found to be advantageous if the method is carried out with a projectile lift designed in the manner described above. This can result in the advantages already described with regard to the projectile lift.

Furthermore, with regard to the above-mentioned problem, a magazine with a projectile lift is also proposed, which is designed in the manner described above. The advantages already described above with regard to the projectile life may result.

Furthermore, it may be advantageous if the magazine is designed in the manner described below. Also, with regard to the magazine, a method for stocking ammunition bodies is proposed below.

The magazine can for the storage of ammunition bodies comprise multiple storage spaces arranged next to each other, wherein the storage spaces are each assigned a holding device for retaining an ammunition body, wherein a conveying device for conveying an ammunition body from one holding device to an adjacent holding device.

With this design ensures it is achieved that individual ammunition bodies can be moved back and forth between the various storage spaces independently of the other ammunition bodies. It is therefore not necessary to move all ammunition bodies and holding devices, but an ammunition body can be selected and then moved to the removal position independently of the other ammunition bodies.

With regard to the removal, it has proved to be advantageous if the ammunition bodies are stored or supported horizontally in the magazine. Due to this design, the ammunition bodies are easier to access than, for example, with upright storage and in addition the ammunition bodies usually have to be fed to the weapon in a horizontal position anyway, so that horizontal storage also simplifies the downstream loading process of the weapon.

Furthermore, it has proved to be advantageous if the magazine has multiple storage levels arranged one above the other, wherein each storage level includes multiple storage spaces. This design leads to dense ammunition body packing, so that the available space is used as well as possible. The number of storage levels and the number of storage spaces per level can thus be adapted to the prevailing space conditions. In practice, for example, three storage levels with eight storage spaces each have proved to be advantageous for military vehicles. This would then correspond to a capacity of 24 ammunition bodies. Nevertheless, only one storage space may be provided at each storage level.

Multiple storage levels have also proved to be advantageous with regard to different ammunition bodies. This is because it is possible that each level is assigned a certain type of ammunition body, so that when selecting an ammunition body or an ammunition body type, this can be removed from the corresponding level without having to move the ammunition bodies of the other levels.

In order to move the ammunition bodies of the different levels to a removal position, it has proved to be advantageous if a projectile lift is provided. In the case of ammunition loading, the projectile lift can transport the ammunition bodies to be stored to their corresponding storage level and then transfer them back from the storage level to a removal position when the ammunition bodies are removed. It may be advantageous if the magazine has a common removal position for multiple ammunition bodies, in particular a common removal position for all ammunition bodies for the removal of the ammunition bodies from the magazine. The ammunition bodies can only be removed from the magazine at a firmly defined point and only at this point will a suitable space or a suitable removal space be required in the direction of removal after the magazine.

It has further proved to be advantageous if the magazine has two storage areas, wherein a projectile lift is arranged between the two storage areas for conveying the ammunition bodies between the storage levels. This design reduces the path of the ammunition bodies from their storage space in the magazine to the projectile lift. The projectile lift can be arranged in the middle of the magazine, so that the two storage areas are of the same size and accordingly the same number of storage spaces is available on both sides of the projectile lift. The ammunition bodies of the two storage areas can be fed to the projectile lift independently of each other, which simplifies the selection of ammunition bodies, for example. The division of the magazine into two parts also makes it possible to directly select twice the number of different ammunition bodies. For example, if there are three storage levels, a different type of ammunition body may be present not only at each storage level, but also in each storage area of each storage level.

With regard to the magazine, it has proved to be advantageous if at least one conveying device is assigned to the storage levels for conveying the ammunition bodies in the respective storage level. By means of the conveying device, the ammunition bodies can be moved back and forth in the horizontal direction between the individual storage spaces of a storage level.

Furthermore, it has proved to be advantageous if the storage levels are designed as stack stores in which the ammunition bodies are stored according to the last-in-first-out principle. Such a stacking structure can include a small installation space, since no space is needed to move the ammunition bodies past each other. Furthermore, only a single or at least one storage level may be provided, which is designed as stack storage and in which the ammunition bodies are stored accordingly.

During ammunition loading, the ammunition bodies can first be moved through the projectile lift to the appropriate storage level and then moved by the conveying device in a storage direction until they have reached their final storage space. During removal, the ammunition bodies are then conveyed by the conveying device in the opposite removal direction from their respective storage space to the projectile lift. When moving the ammunition bodies to or from their final storage space, the conveying device may move the

ammunition bodies past multiple storage spaces, depending on how many ammunition bodies are already at the corresponding storage level.

If, for example, a storage level is still empty and is to be gradually filled with multiple ammunition bodies, the conveying device first transports the first ammunition body to the storage area that is furthest from the projectile lift. The ammunition body passes through the storage areas that lie between the projectile lift and the final storage area before arriving at it. During removal, the conveying device may move the ammunition bodies accordingly towards the projectile lift. Since all storage spaces of the storage level or the storage area of the storage level are passed through between the storage area of the ammunition body to be removed and the projectile lift, the ammunition body nearest to the projectile lift must always be removed first at each storage level.

In a design development, it has proved to be advantageous if at least one conveying device is provided between the storage levels. This design makes it possible to convey the ammunition bodies with the fewest possible conveying devices, which reduces the installation volume of the magazine. If three storage levels are provided, two conveying devices may be provided, one between the middle and lower storage levels and one between the middle and upper storage levels. In this respect, the conveying device may move both ammunition bodies that are arranged below the conveying device and ammunition bodies that are arranged above it. It is possible to move multiple ammunition bodies at the same time, even in different storage levels, with one conveying device. Nevertheless, each storage level may also have its own conveying device assigned to it, or some storage levels may have only one, and other storage levels may be assigned multiple conveying devices. Furthermore, conveying devices may also be provided which are arranged below or above a storage level, but not between two storage levels. For example, a conveying device may be arranged below the lowest storage level or above the highest storage level.

To drive the conveying device, it may be advantageous if each conveying device has a single level drive. Furthermore, it is also possible that only one drive is provided for all conveying devices or for all conveying devices in a storage area. The conveying devices can then be coupled to each other accordingly, for example via a belt drive.

With regard to the constructive design of the conveying device, it has proved to be advantageous if it has at least one rotatable conveying shaft for conveying the ammunition bodies. The conveying shaft may be arranged between two adjacent holding devices. With regard to the arrangement of the conveying device, between does not mean that the conveying shaft is precisely arranged between two holding devices, but above and between or below and between the holding devices. Ammunition bodies can be conveyed from a storage space to an adjacent storage space by means of the conveying shaft. The holding device can first be moved to a transfer position in which it is possible to insert ammunition bodies into the holding device or to remove them from the holding device. Subsequently, the ammunition bodies can then be conveyed by means of the rotatable conveying shaft from one holding device to the other holding device. The conveying shafts can extend parallel to the longitudinal axes of the ammunition bodies or the holding devices. Furthermore, a conveying shaft may also be arranged between the projectile lift and the first holding device. The design of the conveying devices may be independent of the positioning of the conveying devices.

The magazine may have two, in particular parallel, base plates, between which the conveying device or the conveying shafts are rotatably mounted. For storage, the base plates may have a hole pattern with multiple holes. The conveying shafts can be inserted into the corresponding holes. The base plates can be spaced apart from each other by multiple rods, in particular four. The holding devices or the retaining shells of the holding devices may be rotatably supported between the two base plates. The longitudinal axes or the rotation axes of the holding devices can be arranged parallel to each other, so that a matrix-like arrangement results. Furthermore, the longitudinal axes or the rotational axes of the holding devices may be arranged perpendicular to the base plates.

It is also advantageous if the conveying shaft has at least one conveying wheel with at least one receiving contour for receiving an ammunition body. When conveying an ammunition body, it can be received in the receiving contour and then conveyed by the rotation of the conveying shaft. The receiving contour may be adapted to the ammunition body geometry for the safe transport of the ammunition bodies, so that the ammunition bodies cannot slip during conveying. It may be advantageous if the receiving contour is concave. In order to retain the ammunition bodies securely when conveying from one holding device to another holding device, it has proved to be particularly advantageous if each conveying shaft has two conveying wheels. For example, one conveying wheel can engage the rear of the ammunition body and one conveying wheel can engage the middle area of the ammunition body, which is usually the heaviest. An additional conveying wheel for the front part of the ammunition bodies is also possible. The transport wheels of a conveying shaft may be connected to each other by a strut and rotationally coupled to each other by the strut.

Furthermore, it may be advantageous if the conveying wheel is designed as a star wheel, in particular with four receiving contours. If the conveying wheel has four receiving contours, the conveying wheel may be rotated by a quarter of a rotation to convey an ammunition body. This has proved to be advantageous in practice. If multiple conveying wheels are provided, each conveying wheel can be designed as a star wheel.

In order to rotate the conveying shaft and thus also the conveying wheels, it has proved to be advantageous if the conveying shaft has a drive wheel. The drive wheel can be connected to the strut and can thus also be rotationally coupled to the conveying wheels. The drive wheel can be arranged at one end of the conveying shaft and driven by a chain or belt drive. Furthermore, it is also possible that the drive wheel is part of a drive motor, especially if each conveying shaft is driven by its own drive motor.

It has also proved to be advantageous if the conveying shafts of a conveying device can be rotated by means of a common level drive. By means of the common drive, all conveying shafts of a conveying device can thus be rotated synchronously and it is not necessary to drive all conveying shafts individually. The drive wheels of the conveying shafts can be coupled to each other, for example via a chain or a belt. Furthermore, it is possible that the drive shafts of different conveying devices are also coupled to each other, whereby the number of required drives can be reduced even further. Nevertheless, it has proved to be advantageous in terms of reliability if only the conveying shafts of a conveying device are coupled to each other. Alternatively, it is also possible to provide a separate drive for all conveying shafts.

If a conveying device is provided above a storage level and a conveying device is provided below a storage level, it may be necessary for the conveying shafts of the two conveying devices to rotate in different directions for conveying the ammunition bodies. If, for example, an ammunition body is to be moved in the storage direction, it may be necessary that the conveying shafts arranged above the corresponding storage level must be rotated clockwise and the conveying shafts arranged below the conveying shafts must be rotated counterclockwise, since the ammunition body is conveyed both from above and from below by the respective conveying wheels during conveying.

In a development, it may be provided that two conveying shafts which have a rotation angle offset relative to each other are provided between two adjacent holding devices. Each of these two conveying shafts may have one or more conveying wheels, so that the ammunition bodies can be transferred from the conveying wheels of one conveying shaft to the conveying wheels of the other conveying shaft when conveying from a holding device to an adjacent holding device. This allows better guidance of the ammunition bodies between two holding devices. This double guidance has proved to be particularly advantageous for storage levels with ammunition bodies which are conveyed only by conveying devices arranged above the storage level, for example for the lowest storage level. Furthermore, the ammunition bodies can also be conveyed by means of the double guidance over a greater distance between two adjacent holding devices. This can also be advantageous when conveying from the projectile lift to the first holding device closest to the projectile lift, since this distance may be greater than the distance between two holding devices of a storage level.

In an alternative embodiment, it may be provided that the conveying device has at least one, in particular three, rotatable screw rollers for conveying the ammunition bodies. Ammunition bodies can also be moved back and forth between two adjacent holding devices by means of a screw roller. The screw roller may have a corkscrew-like screw guide, which moves the ammunition bodies linearly in the storage direction or in the removal direction during a rotation. For safe conveying of the ammunition bodies, three screw rollers have proved to be advantageous, wherein one may be arranged in the front part, one in the middle part and one in the rear part of the ammunition body or the holding device.

It has further proved to be advantageous if the screw roller extends perpendicular to the longitudinal axis of the holding device. Due to this design, the ammunition bodies can already be conveyed in a storage level by means of just one screw roller. However, it can be advantageous if multiple, in particular three, screw rollers are provided, each of which is arranged in parallel and which extends perpendicular to the longitudinal axis of the holding device of the level. If the conveying device has a conveying shaft, the required number of conveying shafts depends on the number of holding devices. With regard to the holding device, the terms longitudinal axis and rotation axis are used synonymously.

The number of conveying shafts per level may correspond to the number of holding devices per level, since a respective conveying shaft may be arranged between the adjacent holding devices of a level and additionally between the projectile lift and the first holding device. The screw rollers, on the other hand, cannot be coupled to the number of holding devices. This is because the number of holding devices provided only has an influence on the length of the

11

screw rollers, but not on the number. In this respect, the number of screw rollers can be independent of the number of holding devices.

From a design point of view, it has also proved to be advantageous if the screw roller has a constriction for the holding device. The constriction allows the vertical distance of the screw roller and the ammunition bodies retained in the holding device to be reduced, which allows reliable conveying. Due to the constriction, the screw roller can rotate and the holding device cannot prevent a corresponding rotation. It can be advantageous if the screw roller has a constriction for each holding device of the respective storage level. The constriction and the screw guide may be arranged alternately one after the other, so that a constriction is provided in the region of the holding devices and a screw guide is provided between the holding devices for conveying the ammunition bodies.

The screw rollers may each have a drive wheel by means of which the screw rollers can be rotated to convey the ammunition bodies. It can be advantageous if the screw rollers of a conveying device are driven by a level drive, so that the screw rollers of a conveying device rotate synchronously. The drive wheels of the individual screw rollers can, for example, be coupled to each other or to the level drive via chains or belts for this purpose. Analogous to the drive of the conveying shafts, only one drive per conveying device must therefore be provided.

In a development, it is proposed that the magazine has guide rails for guiding the ammunition bodies from the holding device to the conveying device. By means of the guide rails, reliable transfer of the ammunition bodies from a holding device to the conveying device and vice versa can be ensured. The guide rails can be arranged above and below each storage level, so that the ammunition bodies are each guided between two guide rails. The conveying wheels, in particular the conveying wheels engaging the ammunition bodies in the middle, may be designed as double wheels and may engage around the guide rails from both sides. The guide rail may have a bore through which the struts of the conveying unit can extend for this purpose. The guide rail can be designed as a sliding rail and can be made of a slidabile material.

In order to convey the ammunition bodies out of the magazine, it has proved to be advantageous if a push-out device, for example in the form of a thrust element, a rigid backed chain or a driving element is provided. The push-out device can be used to push an ammunition body out of the projectile lift in the removal position, for example towards the vehicle interior.

Furthermore, a vehicle, in particular a military land vehicle, with a magazine of the type described above is proposed. This can result in the advantages already described with regard to the magazine.

The vehicle may have a vehicle hull and a turret rotatable relative to the hull. The turret may have a large-caliber weapon with which the ammunition bodies can be fired. The magazine can be arranged in the vehicle hull or in the turret.

In the ammunition body removal direction, a removal space may be arranged behind the magazine, which is required for the removal of the ammunition bodies from the magazine or for pushing the ammunition bodies out of the magazine. Since the ammunition bodies, in particular all the ammunition bodies in the magazine can only be removed or pushed out in a single predefined removal position, the removal space is smaller than the magazine and this can be about the size of an ammunition body. In this respect, a free space which is not required for the removal of the ammu-

12

nition bodies may be provided in addition to the removal space. The free space can extend around the removal space and to the walls of the hull or turret. The free space can be located above and below as well as to the left and right of the removal space or the ammunition body. Since the free space is not needed for the removal of the ammunition body, this region can be used in another way, for example for the storage of equipment. This design also represents, for example, a significant difference from rack magazines, in which a removal space must be kept in front of the entire magazine for the removal of the ammunition bodies and thus a separate removal position is provided for each ammunition body.

Furthermore, a method for storing ammunition bodies in a magazine is proposed, which allows fast access times even with different types of ammunition.

The method can specify that the ammunition bodies are conveyed by a conveying device from a holding device to an adjacent holding device. Due to this method, individual ammunition bodies are moved back and forth between the various storage spaces independently of the other ammunition bodies. It is not necessary to move all ammunition bodies and holding devices together, but an ammunition body is selected and then conveyed independently of the other ammunition bodies from a holding device to an adjacent holding device. To store the ammunition bodies in the magazine, they are moved in a storage direction from holding device to holding device until they have reached their final position in the magazine. The final position or the final storage space corresponds to the storage space where the ammunition body remains for a longer period of time after storage and which is not just passed through. In order to remove the ammunition bodies from the magazine, they are moved in the opposite removal direction to the projectile lift. This then transfers the ammunition bodies to a removal position in which the ammunition bodies can be removed from the magazine.

It can be advantageous if the magazine for the method is designed in the manner described above. The advantages already described with regard to the magazine may result.

Furthermore, it can be advantageous if the holding device is designed in the manner described below.

The holding device for ammunition bodies may have two mutually relatively movable retaining shells, which form a retaining region in which an ammunition body can be retained, wherein at least one retaining shell can be rotated around a rotation axis and wherein the rotation axis can pass through the retaining region.

This design allows the holding device to be opened and closed with a smaller space requirement. This is because the rotation axis of the retaining shell runs through the retaining region, the distance of the longitudinal axis of the ammunition body from the rotation axis of the retaining shell and thus also the space required for opening is reduced compared to the clamp solution. The retaining shell therefore does not have to be moved as far away from the ammunition body to open and close the holding device.

It has proved to be advantageous if both retaining shells can be rotated around a common rotation axis. This allows rapid opening and closing of the holding device or a rapid rotation of the retaining shells between the retaining position and the transfer position.

Furthermore, it has proved to be advantageous if the rotation axis of the retaining shell aligns with the longitudinal axis of a retained ammunition body. This design allows the holding device to be opened and closed without the need for additional space. Both retaining shells can move in a

13

round contour when opening and closing, and the distance of the retaining shells from the rotation axis can remain constant. The rotation axis can run centrally through the retaining region. Since ammunition bodies are rotationally symmetrical, the retaining region also has a correspondingly round contour, which can match the external diameter of the ammunition bodies.

Furthermore, it has proved to be advantageous if the holding device can accommodate the ammunition bodies horizontally. Especially in magazines in military vehicles, it has proved to be a good idea to arrange the ammunition bodies horizontally, since the ammunition bodies are then much more accessible in contrast to upright storage. Furthermore, horizontal ammunition bodies in a military vehicle usually already point in the firing direction, so that the ammunition bodies can be inserted comparatively easily into the weapon barrel and do not have to be rotated 90 degrees in elevation first.

With regard to the design of the retaining shells, it has proved to be advantageous if they are designed as cylinder segments. It can be advantageous if the central axes of the cylinder segments correspond to the rotation axis. This design allows reliable accommodation of ammunition bodies, as they are also cylindrical.

Furthermore, it has proved to be advantageous if the segment angles of the retaining shells add up to no more than 180 degrees. Due to this design, simple ejection of the ammunition body from the retaining shells is achieved. The segment angle refers to the angle that includes the connection of one end of a retaining shell in cross-section to the rotation axis and the connection of the corresponding other end to the rotation axis. The corresponding connections are at right angles to the rotation axis. The larger the segment angle(s), the more contact surface is available for the ammunition bodies and the more stable are the retaining shells. The segment angle must therefore be sufficiently large so that even heavier ammunition bodies can be safely received and retained. In this respect, it may be advantageous if the sum of the segment angles of the two retaining shells is between 90 and 180 degrees, more specifically between 140 and 180 degrees, more specifically between 170 and 180 degrees and even more specifically between 175 and 180 degrees.

According to a design, the retaining shells have different segment angles. The retaining shell with the larger segment angles can carry correspondingly more weight than the retaining shell with the smaller segment angle. In this respect, the retaining shell with the larger segment angle may be arranged in the retaining position below the ammunition body and the retaining shell with the smaller segment angle may be arranged above the ammunition body. The segment angle of the one retaining shell may be between 90 and 175 degrees, more specifically between 100 and 160 degrees, more specifically between 110 and 140 degrees and even more specifically between 115 and 130 degrees. In practice, a segment angle of 120 degrees has proved to be advantageous. The segment angle of the other retaining shell can be between 30 and 100 degrees, more specifically between 40 and 80 degrees and even more specifically between 50 and 70 degrees. In practice, 60 degrees has proved to be beneficial.

In a development, it is proposed that the two retaining shells can be rotated relative to each other around the rotation axis. In order to open the holding device and transfer it to the transfer position, in which the ammunition bodies can be inserted into the holding device or into the retaining region, the two retaining shells can be moved

14

relative to each other around the rotation axis. In order to close the opened retaining shell which is in the transfer position, so that the ammunition body is then retained in the retaining shell or in the retaining region, the two retaining shells can be moved in the opposite direction.

For moving the retaining shells, it can be advantageous if they can be moved relative to each other by means of a retaining shell drive. One retaining shell drive can offer advantages over movement of the retaining shells with two drives, especially with regard to costs. In this respect, it can be advantageous if the retaining shells are movable relative to each other by means of a single common retaining shell drive. Furthermore, the use of only one drive also reduces the probability of failure. The movements of the retaining shells can be force-coupled, so that a movement of one retaining shell leads to a movement of the other retaining shell. The two retaining shells are then not movable freely and independently of each other, so that firmly defined retaining positions and transfer positions result. The coupling also prevents one of the two retaining shells from moving unintentionally, thus reducing the risk that an ammunition body in the retaining position will not be retained securely or cannot be removed from the holding device or introduced into the holding device in the transfer position.

In this respect, it also can be advantageous if the two retaining shells are movable in opposite directions. If, for example, one of the retaining shells is rotated clockwise around the rotation axis, the other retaining shell can be rotated counterclockwise.

To realize the movement of the retaining shells, it is proposed that the retaining shell drive is connected to both retaining shells via a gearbox. The gearbox can ensure that the two retaining shells can be moved in the opposite direction relative to each other with just one drive.

From a design point of view, it has proved to be advantageous if the gearbox is arranged in an end region of the retaining shells. The gearbox is therefore easily accessible from the outside, which simplifies maintenance. The gearbox may be arranged at the end region of the retaining shells where the rear end of the ammunition bodies is accommodated. In this respect, the gearbox can then bound the retaining region to the rear. Alternatively, it is also possible to arrange the gearbox as well as the retaining shell drive at the front end of the retaining shells.

Furthermore, the retaining shells at the opposite end region can be mounted on a rotary bearing. Due to such a bearing on both sides of the retaining shells, the acting forces can be absorbed reliably. The retaining region or the retained ammunition bodies may be located between the two retaining shells and between the rotary bearing and the gearbox. In this respect, the ammunition bodies are then retained in the holding device securely in the retaining position in each direction and cannot move.

With regard to the design of the gearbox, it has proved to be advantageous if it is designed as a planetary gearbox. A planetary gearbox enables a contrarotating movement of the two retaining shells around a common rotation axis with only one drive in a simple design.

The planetary gearbox can have a hollow wheel with internal toothing and a sun wheel with external toothing. Between the hollow wheel and the sun wheel, multiple planetary wheels may be provided, which mesh with the hollow wheel and with the sun wheel. For uniform power transmission, three evenly distributed planetary gears have proved to be advantageous. The sun wheel and the hollow wheel can both be rotatable around the rotation axis.

15

The planetary gears can be rotatably mounted on a bridge and connected to each other, so that they cannot move relative to each other. The retaining shell drive can be connected to the bridge, for example by a screw connection. When the sun wheel is rotated in one direction around the rotation axis, the planetary gears ensure that the hollow wheel rotates in the opposite direction. The hollow wheel can be connected to one of the retaining shells and the sun wheel can be connected to the other retaining shell so that both retaining shells can then rotate in opposite directions around the rotation axis. Alternatively, it is also possible to drive the hollow wheel by means of the retaining shell drive. Then the sun wheel rotates accordingly in the opposite direction.

In addition to the relative movement of the two retaining shells, it has also proved to be advantageous if the two retaining shells can be rotated together around the rotation axis by means of a rotary drive. This allows a wider range of applications of the holding device. By a corresponding rotation, it is further achieved that ammunition bodies are introduced into the holding device from any direction in the transfer position or that ammunition bodies can be ejected from the holding device in any direction. Furthermore, the two retaining shells in the transfer position can be transferred to a grabbing position by a joint rotation around the rotation axis and oriented in such a way that they can grab an ammunition body from above. If the holding device or the two retaining shells are then transferred from this grabbing position to the retaining position, the ammunition body is secured in the holding device and can then be moved, for example, together with the holding device. In this respect, ammunition bodies can also be grabbed with the holding device and the holding device can be designed as a type of grabber. The grabbing position therefore corresponds to a transfer position in which both retaining shells were rotated together around the rotation axis by 90 degrees.

Due to the rotation of the two retaining shells, ammunition bodies can be ejected from the holding device in any direction, in particular to the right and left. This can be particularly advantageous if the holding device is used in a projectile lift or in a magazine.

The two retaining shells can be rotated together around the rotation axis without moving relative to each other, i.e. are relatively free of movement. The rotary drive can rotate the retaining shell drive, the gearbox and both retaining shells together around the rotation axis for this purpose. The planetary gears of the gearbox can be coupled to the rotary drive via the bridge. For this purpose, the bridge can, for example, be connected to a gear ring, which can be rotated by the rotary drive. The rotary drive can be arranged above the retaining shell drive.

With regard to the retaining shells, it has proved to be advantageous if the two retaining shells are opposite each other in a retaining position in such a way that an ammunition body is retained between the two retaining shells and the two retaining shells are arranged in a transfer position in such a way that an ammunition body can be ejected from the two retaining shells. In the retaining position, the ammunition body may lie in one of the two retaining shells, in particular in the larger retaining shell, and the other retaining shell may be opposite the retaining shell and thus secure the ammunition body. In this way, the ammunition bodies can be retained in a form-fitting way. The two retaining shells are then arranged on opposite sides of the ammunition body. In order to remove the ammunition body from the holding device or to eject it from the holding device, the two

16

retaining shells can be moved to the transfer position in which the ammunition body is no longer secured.

Furthermore, it has proved to be advantageous if the two retaining shells are in contact with each other in the transfer position. Due to this position of the two retaining shells, it is achieved that ammunition bodies can be removed from the holding device or inserted into the holding device. If the two retaining shells are in contact with each other, the form fit is removed accordingly. The two retaining shells can be in contact with each other edge to edge, but in the transfer position the two retaining shells can also be in contact with each other in such a way that they are at least partially arranged one behind the other and overlap. Since the grabbing position basically only corresponds to a rotated transfer position, in the grabbing position the two retaining shells can be in contact with each other accordingly.

In order to simplify the removal of ammunition bodies, it has proved to be advantageous if one of the retaining shells has an ejection device for ejecting an ammunition body. A certain force can be applied to an ammunition body by means of the ejection device, which facilitates the removal or ejection of the ammunition body. The ejection device can be designed as an ejection latch and in particular as a spring. Due to the design as a spring, no additional activation or electrical energy is required to eject the ammunition body from the holding device. When inserting or receiving the ammunition body, the ammunition body can preload the ejection device so that it then ensures that the ammunition body is ejected from the holding device when the retaining shells are transferred to the transfer position. The ejection device may be arranged in the retaining shell with the larger segment angle, since the main load of the ammunition body can weigh on this retaining shell. It can be advantageous if the ejection device is arranged in the region of the center of gravity of the ammunition body, in particular in the middle of the retaining shell. However, it is also possible to provide for multiple ejection devices distributed over the length of the retaining shell. As a result, reliable ejection of the ammunition body can be achieved without it tilting. The longitudinal axis of the ammunition body then remains parallel to the rotation axis of the retaining shells.

Furthermore, it has proved to be advantageous if an ejection mechanism with at least one ejection latch and an ejection drive for moving the ejection latch is provided. The ejection latch can be moved by means of the ejection drive and thus the ammunition body can be ejected from the retaining shell.

The ejection mechanism can be designed in such a way that the ejection latch can be operated by means of a relative movement of the retaining rollers. The ejection latch can thus be force-coupled to the retaining rollers so that the ammunition bodies are ejected automatically if the retaining rollers take up a predefined position, in particular the transfer position.

The ejection latch may have two latch elements connected to the retaining shell at one end, which are swiveled to eject an ammunition body. It can be advantageous if the two latch elements are swiveled towards each other or at least one latch element is swiveled towards the other latch element. For example, one latch element may be swiveled clockwise and the other latch element may be swiveled counterclockwise. At the end not connected to the retaining shell, the latch elements may have rollers that can ensure that the ammunition body is reliably ejected and does not jam. If the ammunition body is in the retaining shell, the ends of the latch elements or the rollers may be in contact with the lower half of the ammunition body, so that when the latch elements

are swiveled, the ammunition body is moved away from the retaining shell in which the latch elements are supported.

Furthermore, it has proved to be advantageous if the ejection mechanism is designed in such a way that the ammunition bodies are ejected in a certain direction regardless of gravity. In this respect, the ammunition bodies can be ejected from the retaining shells not only downwards, but also, for example, laterally and to a certain extent upwards.

Furthermore, it has proved to be advantageous if the ejection latch protrudes over the edge of the lower retaining shell. The ejection latch may thus have a larger segment angle than the retaining shell, in particular than the retaining shell with the larger segment angle. In this respect, the ammunition body can also be additionally secured in the retaining shell by the ejection latch.

With regard to the reliable ejection of the ammunition bodies, it has proved to be advantageous if multiple, in particular three, ejection latches are provided. One ejection latch may be provided for the rear region of the ammunition body and two ejection latches for the front region of the ammunition body.

According to a development, it is provided that the ejection drive has a toothed segment coupled to one of the two retaining shells and an ejection pinion rotatably connected to the other retaining shell, wherein with a relative movement of the retaining shells, the toothed segment rotates the ejection pinion and thereby actuates the ejection latch. In this respect, the ejection of the ammunition bodies can be positively controlled by the relative movement of the retaining shells. No additional motor is required to drive the ejection latches. The ejection pinion can, for example, be rotationally coupled by means of a rod coupling to one or more ejection latches. In particular, the ejection pinion is rotationally coupled to at least one latch element, so that when the ejection pinion is rotated by the toothed segment, the latch element is also rotated accordingly and the ammunition body is basically ejected automatically.

The toothed segment may be designed in such a way that it does not act on the ejection pinion in a certain rotation region of the retaining shell and actuates the ejection pinion in another rotation region. The retaining shells can thus be moved relative to each other in a certain region without the ejection latches being activated. This goes hand in hand with the fact that the ammunition body can only be ejected when the retaining shells have been rotated far enough. In practice, for example, it has proved to be advantageous if the toothed segment only comes into contact with the ejection pinion when the retaining shells only have to be rotated relative to each other by less than 45 degrees, more specifically in one case by less than 30 degrees, more specifically by less than 25 degrees and even more specifically by 22 degrees until they are in contact with each other. The ejection latches are then only activated in this last swivel range.

It may also be advantageous if the toothed segment comes into contact with a different ejection pinion during a clockwise rotational movement of the retaining shell rather than with a counterclockwise rotational movement. Thus, an ejection pinion may be provided for an ejection to the right and an ejection pinion may be provided for an ejection to the left.

It also can be advantageous if the toothed segment and the drive pinion are not arranged within the retaining region, so that this is not reduced or impaired. A toothed segment may be provided in the front region of the retaining shell and another toothed segment may be provided in the rear region of the retaining shell. The same can also apply to the ejection

pinions, wherein there may be two pinions in both the front and rear regions, one for an ejection to the right and one for an ejection to the left.

In particular, if the retaining shells are adapted to the contour of the ammunition bodies and then do not have the same distance from each other or from the rotation axis, in particular in the front and rear regions, it may be necessary that the ratios between the front toothed segment and the front ejection pinions and between the rear toothed segment and the rear ejection pinions are not the same. In this respect, the number of teeth of the front and rear toothed segments and/or the number of teeth of the front and rear ejection pinions may be different. Due to this design, it can be achieved that the ejection latches or the latch elements of the ejection latches are swiveled in the same direction during a rotational movement of the retaining shells.

In a development, it is proposed that the retaining shells are designed in such a way that they are adapted to the contour of the ammunition body to be retained. Due to this adaptation, it can be ensured that the ammunition body cannot move between the two retaining shells and is therefore retained securely. The distance between the retaining shells and the rotation axis may be greater in the rear region of the retaining shells than in the front region. This goes hand in hand with the fact that the ammunition bodies are also narrower in the front region than in the rear region due to the aerodynamics. In this respect, the retaining region can be ammunition body-shaped.

The retaining shells can extend over the entire length of the projectile. The retaining shells may have a length of at least 300 mm, more specifically at least 500 mm, more specifically at least 700 mm, more specifically at least 900 mm, more specifically at least 1100 mm and even more specifically at least 1300 mm. The retaining shells and the retaining region can be designed to accommodate 120 mm caliber ammunition.

The ammunition bodies can be designed as large-caliber ammunition bodies that can be fired through the weapon barrel of a military vehicle. For example, they can be projectiles with a caliber of 120 mm. It can be cartridge ammunition, cartridge ammunition with a propellant charge separated from the projectile or propellants or projectiles themselves. In particular, it is lethal ammunition.

BRIEF DESCRIPTION OF DRAWINGS

Further advantages and details of the magazine and the method will be explained in more detail below with the help of the attached figures using exemplary embodiments. In the figures:

FIG. 1 shows a magazine in a perspective side view;

FIG. 2 shows a perspective detailed view of a storage area of the magazine according to FIG. 1;

FIG. 3 shows a sectional view through the magazine according to FIG. 1;

FIG. 4 shows a further sectional view through the magazine to visualize the drive of the conveying device;

FIG. 5 shows the magazine according to FIG. 4 in a perspective side view;

FIG. 6 shows different views of conveying an ammunition body from one holding device to an adjacent holding device;

FIG. 7 shows a sectional view through a magazine in a further design;

FIG. 8 shows a detailed view of the conveying device of the magazine according to FIG. 7;

FIG. 9 shows a perspective view of the magazine according to FIG. 7;

FIG. 10 shows a perspective side view of the projectile lift of the magazine;

FIG. 11 shows a perspective detailed view of the projectile lift;

FIG. 12 shows a perspective representation of the projectile lift in the removal position;

FIG. 13a shows a perspective view of the projectile lift during the storage of an ammunition body;

FIG. 19b shows a perspective view of the holding device and the ejection mechanism.

DETAILED DESCRIPTION

The design of the magazine 1 as well as loading ammunition into the magazine 1 and the removal of ammunition bodies 100 from the magazine 1 will be described below in more detail, before the design of the holding device 4 and the design of the projectile lift 7 are discussed in more detail.

The magazine 1 shown in FIG. 1 is used for the horizontal storage of ammunition bodies 100, in particular in the form of 120 mm cartridges, and can be used, for example, in a military vehicle 200. As will be described in more detail below, the magazine 1 can, for example, be equipped with ammunition bodies 100 before an operation, and during an operation the individual ammunition bodies 100 can first be moved to a removal position P, removed from the magazine 1 one after the other, fed to the weapon 203 of the vehicle 200 and then fired.

The magazine 1 has a total of 24 storage spaces 3 for the storage of ammunition bodies 1, wherein an ammunition body 100 can be stored in each storage space 3. Furthermore, an ammunition body 100 can also be accommodated in the projectile lift 7, so that the magazine 1 has a total capacity of 25 ammunition bodies 100. Each storage space 3 is assigned a holding device 4, so that the individual ammunition bodies 100 are retained securely in each storage space 3 and cannot slip.

As can also be seen in the illustration of FIG. 1, the magazine 1 has two base plates 1.1, 1.2 arranged parallel to

each other, which are arranged spaced apart from each other by means of multiple rods 1.3. The base plates 1.1, 1.2 each have a hole pattern 1.4, so that the holding device 4 can be mounted between the two base plates 1.1, 1.2.

5 A projectile lift 7, which divides the magazine 1 into two different storage areas 2, is arranged in the middle of the magazine 1. For the sake of better clarity, in FIG. 1 the right storage area 2 is not equipped with holding device 4, so that the hole pattern 1.4 of the base plates 1.1, 1.2 can be seen. In the left storage area 2, the holding device 4 are also partially not shown, as can also be seen in FIG. 2. In this illustration, only the right storage area 2 and the projectile lift 7 can be seen and the front base plate 1.2 is not shown.

Furthermore, it can be seen that the individual storage spaces 3 are arranged in three storage levels 2.1, 2.2, 2.3 arranged one above the other. The storage levels 2.1, 2.2, 2.3 of each storage area 2 have four storage spaces 3 arranged next to each other and therefore also four holding devices 4 arranged next to each other. The storage spaces 3 of the different storage levels 2.1, 2.2, 2.3 are arranged one above the other in such a way that a matrix-like arrangement of the holding devices and the ammunition bodies 100 results.

In order to load ammunition into the magazine 100 and to populate it with a number of ammunition bodies 100, the ammunition bodies 100 are inserted one after the other into the projectile lift 7. Depending on the storage level 2.1, 2.2, 2.3 in which the respective ammunition body 100 is to be stored, the ammunition body 100 is then moved by the projectile lift 7 to the correct storage level 2.1, 2.2, 2.3. In a next step, the ammunition body 100 is then conveyed from the projectile lift 7 to the first storage space 3 of the corresponding storage level 2.1, 2.2, 2.3 and then moved in the storage direction E until the ammunition body 100 has reached its final storage space 3. Conveying the ammunition bodies 100 from the projectile lift 7 to the first storage space 3 and then to the other storage spaces 3 will be explained in more detail below.

If the magazine 1 is still empty, the first ammunition body 40 100, after it has been conveyed from the projectile lift 7 to the first storage space 3 of the corresponding storage level 2.1, 2.2, 2.3, continues to move three storage spaces 3 in the storage direction E until it has reached the outermost storage space 3. During this conveying, the ammunition body 3 thus 45 passes through all the storage spaces 3 of the respective storage level 2.1, 2.2, 2.3 between the projectile lift 7 and the final storage space 3 of the respective storage level 2.1, 2.2, 2.3 of one of the two ammunition areas 2.

The next ammunition body 100 must then be conveyed 50 50 from the first storage space 3 of the corresponding storage level 2.1, 2.2, 2.3 only by two storage spaces 3 until it has reached its final storage space 3. The further storage spaces 3 of the magazine 1 are then filled in an analogous manner.

When the ammunition bodies 100 are removed, they are 55 55 moved in the removal direction A from their respective storage space 3 to the projectile lift 7. Since the ammunition bodies 100 must always pass through all storage spaces 3 which lie between their final or their current storage space 3 and the projectile lift 7, it is always only possible to convey 60 to the projectile lift 7 the ammunition body 3 of a storage level 2.1, 2.2, 2.3 which is closest to the projectile lift 7. Each storage level 2.1, 2.2, 2.3 or each storage level 2.1, 2.2, 2.3 of the respective storage area 2 thus acts as stack storage and the ammunition bodies 100 can be taken from this stack 65 storage according to the last-in-first-out principle. Although the order of removal of the ammunition bodies 100 of a storage level 2.1, 2.2, 2.3 is thus predetermined, a selection

can be made between the different storage levels 2.1, 2.2, 2.3 and the different storage areas 2 during the removal.

If, for example, all storage spaces 3 of the magazine are occupied by an ammunition body 100, then when removing an ammunition body 100 a selection can be made from six different ammunition bodies 100, namely from the ammunition bodies 100 of the respective levels closest to the projectile lift 7. In this respect, it is also possible that different types of ammunition are stored in the different storage levels 2.1, 2.2, 2.3 and/or in the two storage areas 2 and then a certain type of ammunition body is selected and removed during the removal depending on the requirements.

A conveying device 5 is provided for conveying ammunition bodies 100 from the projectile lift 7 to the first storage space 3 and for moving the ammunition bodies 100 between the individual storage spaces 3 or the individual holding devices 4. The conveying device 5 is provided between the individual storage levels 2.1, 2.2, 2.3, so that at least two conveying devices 5 are provided on each storage side 2.

In one design, the conveying devices 5 have multiple conveying shafts 5.1, which are rotatably mounted between the two base plates 1.1, 1.2 of the magazine. These conveying shafts 5.1 can be seen, for example, in FIG. 5. The conveying shafts 5.1 extend parallel to the horizontal ammunition bodies 100 and each have multiple conveying wheels 5.2, 5.3 designed as radial wheels, which ensure during rotation that the ammunition bodies 100 are conveyed from a storage space 3 to an adjacent storage space 3.

In the design according to FIG. 5, the conveying shafts 5.1 each have two conveying wheels 5.2, 5.3, wherein the first conveying wheel 5.2 is larger than the second conveying wheel 5.3, which is related to the contour of the ammunition bodies 100. This is because the ammunition bodies 100 have a larger diameter in the rear region than in the middle region, which can also be seen, for example, in FIG. 10. The two conveying wheels 5.2, 5.3 are attached to or on a strut 5.4, so that when the strut 5.4 rotates, the two conveying wheels 5.2, 5.3 rotate in unison.

In order to convey the ammunition bodies from one storage space 3 to the next, the ammunition bodies 100 are first moved from the holding device 4 to the conveying wheels 5.2, 5.3. Starting from the position in FIG. 5, the conveying shafts 5.1 are first rotated by about 45 degrees towards the ammunition body 100 to be moved. In a next step, the holding device 4 is then transferred to a transfer position Ü, which allows the removal of the ammunition body 100. The different positions of the holding device 4 are described in more detail below with regard to the other figures.

If the ammunition body 100 is then resting on the conveying shaft 5.1 or on the conveying wheels 5.2, 5.3, the conveying shaft 5.1 is rotated by about 90 degrees towards the adjacent holding device 4 and can then be picked up by the corresponding holding device 4. In order to convey the ammunition body beyond that, the process is continued accordingly and the ammunition body 100 is passed to the next conveying shaft 5.1.

In order to transfer the ammunition bodies 100 in this way from holding device 4 to holding device 4, the corresponding conveying shafts 5.1 are arranged above or below the holding device 4 and between two adjacent holding devices 4, as can be seen in FIG. 3, for example. Furthermore, it can be seen in FIG. 3 that conveying devices 5 are provided only between the storage levels 2.1, 2.2, 2.3. The lower conveying device 5 is thus responsible both for conveying the ammunition bodies 100 in the lowest storage level 2.1 and in the middle storage level 2.2. If, for example, an ammu-

nition body 100 in the lowest storage level 2.1 according to the representation in FIG. 3 is to be moved in the storage direction E, i.e. from right to left, the conveying shafts 5.1 above the lower storage level 2.1 must rotate clockwise. If the same conveying shafts 5.1 are to move the ammunition bodies 100 of the middle storage level 2.2 correspondingly, the conveying shafts 5.1 must be rotated counterclockwise.

Since a conveying device 5 is provided both below and above the middle storage level 2.2, the ammunition bodies 100 of the middle storage level 2.2 are conveyed by both conveying devices 5. According to the illustration of FIG. 3, in order to move the ammunition bodies 100 in the storage direction E, the conveying shafts 5.1 arranged above the middle storage level 2.2 must then rotate clockwise and the conveying shafts 5.1 arranged below the middle storage level 2.2 must rotate counterclockwise. As can also be seen in FIG. 3, a conveying shaft 5.1 is also arranged between the first holding device 4 and the projectile lift 7, so that the ammunition bodies 100 can be moved both from the projectile lift 7 and to the projectile lift 7.

The number of conveying shafts 5.1 per conveying device 5 thus corresponds to the number of holding devices 4 or the number of storage spaces 3 per storage level 2.1, 2.2, 2.3 of each storage area 2. As can be seen in FIG. 3, four conveying shafts 5.1 per conveying device 5 are therefore also provided for the four holding devices 4.

The more precise design of the conveying wheels 5 can be seen in FIG. 5 and FIG. 6. Each conveying wheel 5.2, 5.3 has four concave receiving contours 5.21, 5.31, each offset by 90 degrees from each other. The curvature or the design of the receiving contours 5.21, 5.31 is adapted to the ammunition bodies 100, so that they lie as safely as possible in the corresponding receiving contours 5.21, 5.31 during conveying.

Furthermore, an alternative design is shown in FIG. 6, in which two conveying shafts 5.1 are provided between the holding devices 4 for conveying ammunition bodies 100 from one holding device 4 to an adjacent holding device 4. With this design, a conveying device 5 thus has twice as many conveying shafts 5.1 as holding devices 4 are provided in a storage level 2.1, 2.2, 2.3. As can also be seen in FIG. 6, due to twice the number of conveying shafts 5.1, the ammunition bodies 100 are better guided and transferred from one conveying shaft 5.1 to the other conveying shaft 5.1 and at about half the distance between the two holding devices 4.

If two conveying shafts 5.1 are used between two holding devices 4, it is accordingly necessary to adapt the hole pattern 1.4 in the base plates 1.1, 1.2. This becomes clear when comparing the hole patterns 1.4 of FIG. 5 and FIG. 7. Although no embodiment with two conveying shafts 5.1 between two holding devices 4 is shown in FIG. 7, it can be seen that the base plate 1.1 has two holes between two holding devices 4 or two storage spaces 3, so that two conveying shafts 5.1 can accordingly be mounted.

For driving the conveying shafts 5.1 regardless of whether one or more conveying shafts 5.1 are provided between two holding devices 4, each conveying shaft 5.1 has a drive wheel 5.5 at one end. As can be seen in FIGS. 4 and 5, all conveying shafts 5.1 of a conveying device 5 are connected to a common level drive 6 by a coupling element 5.6 designed as a belt. The conveying shafts 5.1 of a conveying device 5 thus all rotate synchronously when an ammunition body 100 is conveyed from one holding device 4 to an adjacent holding device 4. Since all conveying shafts 5.1 of a conveying device 5 thus always move together anyway, it is not absolutely necessary, for example when adding ammu-

nition to the magazine 1 or when moving the ammunition bodies 100 in the storage direction E, to move the ammunition bodies one after the other, but for example multiple ammunition bodies 100 in a storage level 2.1, 2.2, 2.3 can also be moved simultaneously. Since conveying devices 5 can also move ammunition bodies 100 of different storage levels 2.1, 2.2, 2.3, thus multiple ammunition bodies 100 in different storage levels 2.1, 2.2, 2.3 can also be moved by a conveying device 5.

For guiding the ammunition bodies 100, guide rails 8 are also provided, which also ensure that the ammunition bodies 100 can only be moved in the storage direction E or in the removal direction A during conveying, but not perpendicular to this, for example. As can be seen in FIG. 5, the guide rails 8 are arranged above and below each storage level 2.1, 2.2, 2.3 and extend essentially perpendicular to the ammunition bodies 100 or perpendicular to the conveying shafts 5.1.

In the case of the guide rails 5.8, which are arranged between two storage levels 2.1, 2.2, 2.3, the struts 4.5 of the respective conveying shafts 5.1 extend through the guide rails 5.8 and the guide rails 8 are arranged at the level of the drive wheels 5.2, 5.3. The drive wheels 5.2, 5.3 can each be designed as double wheels and engage around the guide rails 5.8. As a result, in particular, the guide rails 5.8 which are not arranged in the roof area or in the floor area can then be fixed in a defined position. So that the guide rails 5.8 do not hinder a movement of the holding device 4 from the transfer position Ü and the retaining position H, the guide rails 5.8 can be rounded in the corresponding regions, which can be seen in FIG. 5 and also in FIG. 3, for example.

In a further embodiment, the conveying devices 5 may have one or more screw rollers 5.7 instead of the conveying shafts 5.1. This embodiment is shown in FIGS. 7 to 9. As can be seen in particular in FIG. 9, the conveying device 5 has three screw rollers 5.7 of different sizes or diameters arranged parallel to each other, with one screw roller 5.7 arranged in the middle, one in the rear and one in the front of the ammunition bodies 100.

Unlike the conveying shafts 5.1, the screw rollers 5.7 do not extend parallel to the longitudinal axes of the ammunition bodies 100, but perpendicular to them. Accordingly, the screw rollers 5.7 are also not rotatably supported in the base plates 1.1, 1.2, but in corresponding rails that extend between the two base plates 1.1, 1.2. As can be seen in FIG. 9, therefore, not all holes of the hole pattern 1.4 are required, in particular not the holes in which the conveying shafts 5.1 are rotatably supported.

The screw rollers 5.7 have alternating constrictions 5.72 and screw guides 5.71. The screw guides 5.71 serve quite analogously to the conveying shafts 5.1 to transport the ammunition bodies 100 from a holding device 4 to the next holding device 4 and are arranged accordingly between the holding devices 4. The screw guides 5.71 are designed in such a way that the ammunition bodies 100 are guided in these and a rotational movement of the screw rollers 5.7 leads to a linear movement of the ammunition bodies 100 in the storage direction E or in the removal direction A, depending on the direction of rotation of the screw roller 5.7. This becomes clear, for example, in FIG. 8, in which the transport of an ammunition body 100 between the two right holding devices 4 is shown.

The constrictions 5.71 are arranged in the region of the holding device 4 and ensure that the holding device 4 can be moved back and forth between the retaining position H and the transfer position Ü. The constrictions 5.71 also serve in this respect that the screw roller 5.7 can reach closer to the longitudinal axis of the ammunition bodies 100, which

enables safe conveying of the ammunition bodies 100, as can also be seen in the illustration of FIG. 8.

In order to move the ammunition bodies 100 in a storage level 2.1, 2.2, 2.3, the screw rollers 5.7 of a conveying device 5 must be rotated synchronously. For this purpose, the screw rollers 5.7 each have a drive wheel 5.5, which are coupled to each other by one or more coupling elements 5.6 and rotatable by means of a level drive 6.

Before going into more detail below about the more detailed design of the holding device 4 and the projectile lift 7, the positioning of the magazine 1 in the vehicle 200 and the resulting space conditions will first be explained on the basis of FIGS. 18a and 18b.

The vehicle 200 has a vehicle hull 201 and a turret 202 rotatably supported relative to the hull with a large-caliber weapon 203. The magazine 1 is arranged in the rear region of the turret 202 and the ammunition bodies 100 are pushed out of the magazine 1 towards the weapon 203 and then fed to the weapon 203. The supply of the ammunition bodies 100 from the magazine 1 to the weapon 203 can be accomplished both manually by a loader but also, for example, automatically by a suitable loading device.

In the top view of FIG. 18a and in the side section view of the turret according to FIG. 18b, the ammunition bodies 100 still in the magazine 1 can be seen. The removed ammunition body 100 was, as already described above, first conveyed from its storage space 3 to the projectile lift 7 and then moved to the middle storage level 2.2, in which the ammunition body 100 can be pushed out of the magazine 1. Since during removal all ammunition bodies 100 in the magazine 1 are correspondingly first moved to the removal position P and can only then be removed or pushed out, only a small space is required in the region between the magazine 1 and the weapon 203. This can also be seen in the figures. This is because only a small withdrawal space 205 must be kept behind the magazine 1 in the removal position P for the removal of the ammunition body 100, thus in the exemplary embodiment in the middle storage level 2.2 behind the projectile lift 7 in the middle of the magazine 1. The free spaces 204 located next to the removal space 205, on the other hand, can be used in other ways and are not needed for the removal of an ammunition body 100. Due to the defined removal position P, which is identical for all ammunition bodies 100, the space requirement of the magazine 1 or the space requirement for the removal of an ammunition body 100 can be significantly reduced.

The design and function of the holding device 4 is described in more detail below, in particular on the basis of FIGS. 14 to 17.

FIG. 14 shows the holding device 4 in a perspective side view and in a retaining position H. The holding device 4 consists essentially of two retaining shells 4.2, 4.3, which are rotatably coupled to each other in a front end region 4.22 by a rotary bearing 4.6 and in a rear end region 4.21 by a retaining shell drive mechanism 4.9. In the retaining position H, the two retaining shells 4.2, 4.3 are opposite each other in such a way that an ammunition body 100 is accommodated in a form-fitting manner in the retaining region 4.10 located between the two retaining shells 4.2, 4.3 and cannot be removed from the holding device 4. This is also shown, for example, in FIG. 13g.

In order to remove the ammunition body 100 from the holding device 4, it is necessary to move the two retaining shells 4.2, 4.3 relative to each other and to rotate them around the rotation axis D. The movement of the two retaining shells 4.2, 4.3 can be seen, for example, in FIG. 14. In the right position of FIG. 14 the holding device 4 is or the

two retaining shells 4.2, 4.3 are in the retaining position H. In order to remove an ammunition body 100 from the holding device 4, the upper retaining shell 4.2 is rotated counterclockwise and the lower retaining shell 4.3 is rotated clockwise around the rotation axis D until the two retaining shells 4.2, 4.3 are in contact with each other, as can be seen in the left illustration of FIG. 14.

The upper retaining shell 4.2 and the lower retaining shell 4.3 are each designed as cylinder segments and have different segment angles x1, x2. The lower retaining shell 4.3 is larger than the upper retaining shell 4.2 and has a larger segment angle x2, so that the force or weight of the ammunition bodies 100 is distributed over a larger area. The retaining shell 4.2 which has the smaller segment angle x1 only has to absorb a comparatively small force and is primarily used to secure the ammunition body 100 in the lower retaining shell 4.3.

In order for an ammunition body 100 in the transfer position Ü either to be removed from the holding device 4 or to be inserted into the holding device 4, the sum of the segment angles x1, x2 is about 180 degrees, as can be seen in the left illustration of FIG. 14. If the sum of the segment angles were greater than 180 degrees, an ammunition body 100 could not be removed from the holding device 4, even if the two retaining shells 4.2, 4.3 are in contact with each other. If, on the other hand, the sum of the segment angles x1, x2 were significantly smaller than 180 degrees, the strength of the retaining shells 4.2, 4.3 would be reduced.

As can also be seen in FIG. 15 or FIG. 13 h, the two retaining shells 4.2, 4.3 are adapted to the contour of the ammunition body 100. Thus, the distance of the two retaining shells 4.2, 4.3 from the rotation axis D, which also corresponds to the longitudinal axis of the ammunition bodies 100, is greater in the rear end region 4.21 than in the front end region 4.22, exactly as is also the case with the ammunition bodies 100.

The lower retaining shell 4.3 has an ejection device designed as an ejection latch 4.7, which is designed as a passive spring. When inserting an ammunition body 100, the ejection latch 4.7 is tensioned by the weight of the ammunition body 100. When the lower retaining shell 4.3 is rotated around the rotation axis D and moved to the transfer position Ü, the ejection latch 4.7 ensures that the ammunition body 100 is automatically ejected from the holding device 4.

In FIG. 8, for example, it can be seen that the two right retaining shells 4 are located in the transfer position Ü. The ammunition body 100 was initially located in the right holding device 4 and was retained by this in the corresponding storage space 3. In order to move the ammunition body 100 from the magazine 1 to the projectile lift 7 for removal, the holding device 4 was first transferred from the retaining position H to the transfer position Ü. The ammunition body 100 is moved by the ejection latch 4.7 to the conveying device 5, which then conveys the ammunition body 100 to the adjacent holding device 4. To receive the ammunition body 100, this retaining shell 4 is also located in the transfer position Ü, as can be seen in FIG. 8. When the ammunition body 100 has been conveyed by the conveying device 5 and has reached the holding device 4, the two retaining shells 4.2, 4.3 of the holding device 4 are transferred to the retaining position H. The upper retaining shell 4.2 is rotated clockwise around the rotation axis D and the lower retaining shell 4.3 counterclockwise.

If the ammunition body 100 is to be retained in the holding device 4, the holding device 4 remains in the retaining position H. If the ammunition body 100 is to be

conveyed further in the removal direction A, the retaining shells 4.2, 4.3 are rotated further around the rotation axis D until they lie next to each other on the other side of the ammunition body 100. The position of the holding device 4 then corresponds to that of the right holding device 4 of FIG. 8 and the ammunition body 100 can be moved further in the removal direction A.

In order to move the two retaining shells 4.2, 4.3 in the manner described above and to transfer them from the retaining position H to the transfer position Ü or vice versa, the retaining shell drive mechanism 4.9 has a retaining shell drive 4.4 in the form of a motor and a gearbox 4.5. The gearbox 4.5 is designed in such a way that both retaining shells 4.2, 4.3 can be moved by only one motor.

The design of the gearbox 4.5 can be seen in FIG. 16. The gearbox 4.5 is designed as a planetary gearbox and has an outer hollow wheel 4.52, an inner sun wheel 4.51 and three planetary gears 4.53, which mesh with the hollow wheel 4.52 and the sun wheel 4.51. The three planetary wheels 4.53 are connected to each other by a bridge 4.54 and ensure that the hollow wheel 4.52 and the sun wheel 4.51 rotate in opposite directions. When the sun wheel 4.51 is rotated clockwise, the hollow wheel 4.52 thus rotates counterclockwise, but around the same rotation axis D. The hollow wheel 4.52 is connected to the upper retaining shell 4.2 and the sun wheel 4.51 is connected to the lower retaining shell 4.3, so that both retaining shells 4.2, 4.3 can be rotated in the opposite direction around the rotation axis D by a single retaining shell drive 4.51 connected to the sun wheel 4.51.

In addition to the relative movement of the two retaining shells 4.2, 4.3 around the rotation axis D, it is also possible to rotate both retaining shells 4.2, 4.3 together around the rotation axis D. This can be seen in FIGS. 13c and 13h, for example. This is because the holding device 4 is located in the transfer position Ü in both illustrations, yet the two retaining shells 4.2, 4.3 are rotated together by about 90 degrees around the rotation axis D.

In order to rotate the two retaining shells 4.2, 4.3 together, another motor in the form of a rotary drive 4.8 is provided, which can be seen in FIG. 17, for example. For the sake of better clarity, FIG. 17 does not show the retaining shell drive 4.4, but both drives 4.4, 4.8 are shown in FIG. 1 or 2, for example. The rotary drive 4.8 drives a gear ring 4.55 to which the bridge 4.54 is attached. By means of the rotary drive 4.8, the entire gearbox 4.5 and also the retaining shell drive 4.4 are thus rotated around the rotation axis D, without the retaining shells 4.2, 4.3 moving relative to each other. In order to transfer the retaining shells 4.2, 4.3 to their desired position as quickly as possible, both drives 4.4, 4.8 can also be operated simultaneously.

At the storage spaces 3 it is usually not necessary that the two retaining shells 4.2, 4.3 are also rotated together around the rotation axis D, but for the holding device 4 basically the two transfer positions Ü and the retaining position H shown in FIG. 8 are sufficient. The rotary drive 4.8 is primarily required for the projectile lift 7 described below, since the holding device 4 or the retaining shells 4.2, 4.3 can also be rotated into a grabbing position G by means of this. For this reason, no rotary drive 4.8 is provided in the holding device 4 of the various storage spaces 3 of the magazine 1 and the respective retaining shells 4.2, 4.3 are only rotatable relative to each other by the retaining shell drive 4.4.

The corresponding bridges 4.54 therefore do not have to be moved but are screwed to the base plate 1.2 of the magazine 1. Due to the fact that the planetary gears 4.53 are rotatably supported on the bridge 4.54, they thus also serve as a rotary bearing of the holding device 4 on the base plate

1.2. FIG. 1 also shows the configuration of the hole pattern 1.4 on the outside of the base plate 1.2, so that the hollow wheel 4.52 can be accommodated, for example, in the base plate 1.2 and does not protrude from the base plate 1.2. On the opposite base plate 1.1, the rotary bearings 4.6 are plugged into the base plate 1.1, so that the two retaining shells 4.2, 4.3 are also rotatably supported on this base plate 1.1.

The retaining shell drive mechanism 4.9 is located at the end of the holding device 4, which serves to accommodate the lower ends of the ammunition bodies 100. As can be seen, for example, in FIGS. 1 and 2, the retaining shell drive 4.4 of the holding devices 4, which are assigned to the storage spaces 3 of the magazine 1, is arranged on the same side. The level drives 6 for driving the conveying devices 5, on the other hand, are arranged on the other side of the magazine 1, so that the level drives 6 and the retaining shell drives 4.4 are opposite each other relative to the magazine 1.

The common rotation of the retaining shells 4.2, 4.3 is required in particular for the projectile lift 7 described in more detail below on the basis of FIGS. 11 to 13.

FIGS. 19a and 19b will be used below to describe a possibility for driving the ejection latches 4.7 by means of an ejection mechanism 4.11. In the front and rear regions of the retaining shells 4.2, 4.3, an ejection drive 4.11 is provided for this purpose, by means of which the ammunition bodies 100 can be ejected from the retaining shells 4.2, 4.3 laterally and basically also independently of gravity.

As has already been described, the lower retaining shell 4.3 is equipped with multiple ejection latches 4.71, 4.72, namely in the front region with two front ejection latches 4.71 and in the rear region with a rear ejection latch 4.72. Each ejection latch 4.71, 4.72 has two latch elements which can be moved independently of each other and which are pivotably supported at one end in the lower retaining shell 4.3. The right and left latch elements of the front ejection latches 4.71 are each connected to a front ejection pinion 4.15 by means of a rod not visible in the figure. When the ejection pinion 4.15 is rotated, the connected latch elements of the ejection latches 4.71 rotate accordingly. The latch elements of the rear ejection latch 4.72 are connected in a corresponding manner to the two rear ejection pinions 4.14 to be seen in FIG. 19a and can be moved by means of them.

To drive the ejection latches 4.71, 4.72, the respective ejection pinions 4.15, 4.14 of the ejection drives 4.11 must be rotated, namely either the front and rear right ejection pinions 4.14, 4.15 or the front and rear left ejection pinions 4.14, 4.15.

In order to move the ejection pinions 4.14, 4.15 accordingly, the upper retaining shell 4.2 in the front and rear end regions 4.22, 4.21 is respectively connected to a toothed segment 4.12, 4.13, which can be rotated around the rotation axis D together with the retaining shell 4.2. If the upper retaining shell according to the illustration of FIG. 19a is rotated clockwise, the toothed segments 4.12, 4.13 are moved towards the right ejection pinions 4.14, 4.15. However, as long as the toothed segments 4.12, 4.13 have not yet reached the ejection pinions 4.14, 4.15, they do not yet move. Only shortly before the two retaining shells 4.2, 4.1 come into contact with each other do the toothed segments 4.12, 4.13 engage with the ejection pinions 4.14, 4.15. In the example shown, the distance between the two retaining shells 4.2, 4.3 at the beginning of meshing is about 22 degrees. In this last swivel range of the retaining shells 4.2, 4.3, before they contact other, the toothed segments 4.12, 4.13 then turn the drive pinions 4.14, 4.15 counterclockwise.

This movement is transmitted accordingly to the right latch elements of the ejection latches 4.71, 4.72, so that the latch elements then move the ammunition body 100 towards the opening created between the two retaining shells 4.2, 4.3 and thus push it out of the retaining region 4.10 to the left.

When the retaining shells 4.2, 4.3 are then moved back to the retaining position H, the drive pinions 4.14, 4.15 are rotated in the opposite direction until the toothed segments 4.12, 4.13 are disengaged again and the latch elements have again reached the position shown in FIGS. 19a and 19b.

If an ammunition body 100 is to be ejected to the other side, the retaining shells 4.2, 4.3 are accordingly rotated in the opposite direction and the toothed segments 4.12, 4.13 then drive the other drive pinions 4.14, 4.15 accordingly. According to the illustration of FIG. 19a, the left latch elements are then operated and these push the ammunition body 100 out of the retaining region 4.10 to the right. Due to the described forced coupling, no additional motor is required for the ejection of the ammunition bodies 100, but by means of the basically purely passive ejection drive 4.11, the ammunition bodies 100 can be ejected automatically when the retaining shells 4.2, 4.3 have reached the corresponding position, for example the transfer position Ü.

As is noticeable, for example, in a comparison of the ejection latches 4.71, 4.2 of FIGS. 19a and 19b with those of FIG. 13i, the ejection latches 4.7 shown in FIG. 13i engage rather in the lower region of the ammunition bodies 100, whereas the ejection latches 4.71, 4.72 according to FIGS. 19a, 19b rather press the ammunition bodies 100 laterally from the retaining rollers 4.1, 4.2. This is accompanied by the fact that the latch elements of the ejection latches 4.71, 4.72 are supported in the retaining shell 4.3 in the mutually facing end regions, whereas the latch elements of the ejection latch 4.7 according to FIG. 13i are pivotably supported in the end regions facing away from each other. The ejection latches 4.71, 4.72 can therefore also protrude from the retaining shell 4.3 and contribute to secure lateral support of the ammunition bodies 100 in the retaining shell 4.3.

As can be seen in FIG. 1, the projectile lift 7 is arranged in the middle of the magazine 1 and divides the magazine 1 into two storage areas 2, each of which has 12 storage spaces 3 for the ammunition bodies 100. These storage spaces 3 are divided into three storage levels 2.1, 2.2, 2.3 arranged one above the other and each with four storage spaces 3. By means of the projectile lift 7, the individual storage levels 2.1, 2.2, 2.3 can be populated with ammunition bodies 100 or ammunition bodies 100 can be conveyed from the storage levels 2.1, 2.2, 2.3 to the removal position P, at which the ammunition bodies 100 can be removed from the magazine 1 or at which the ammunition bodies 100 can be conveyed out of the magazine 1.

In the illustration of FIG. 11, the projectile lift 7 is shown in a perspective representation isolated from the magazine 1. The projectile lift 7 has a receiving tray 7.1, which can be moved in the vertical direction and a holding device 4, which can also be moved in the vertical direction. The holding device 4 used in the projectile lift 7 is the same holding device 4 which is also used to hold the ammunition bodies 100 in the storage spaces 3 and which has already been described above.

The projectile lift 7 also has two linear drives 7.2, by means of which the holding device 4 can be moved in the vertical direction. Each of the two linear drives 7.2 has two threaded spindles 7.21, 7.22, which are rotatably supported at their lower ends in a bearing rail 7.25 and which extend parallel to each other in the vertical direction and perpen-

dicular to the rotation axis D of the holding device 4 or to the longitudinal axis of the ammunition body 100. In order to move the holding device 4, a guide element 7.6 is provided, which is arranged as a type of a spindle nut on the two threaded spindles 7.21, 7.22 of the linear drive 7.2. If the two threaded spindles 7.21, 7.22 rotate uniformly, the guide element 7.6 can thus be moved up and down in the vertical direction.

As can also be seen in FIG. 11, the holding device 4 is mounted on the guide element 7.6, so that the holding device 4 can be moved accordingly by means of the guide element 7.6. In order to ensure uniform movement of the holding device 4, it is connected both in the front end region 4.21 and in the rear end region 4.22 to a corresponding guide element 7.6, which can be moved in each case by means of a linear drive 7.2. Thus, the weight of an ammunition body 100 can be supported by two linear drives 7.2 or correspondingly by four threaded spindles 7.21, 7.22.

In order to securely connect the projectile lift 7 to the magazine 1 or to the two storage areas 2, the bearing rail 7.25 can be connected to a base plate 1.1, 1.2 of the magazine 1 and also the threaded spindles 7.21, 7.22 can be rotatably connected to the magazine 1. Thus, the forces generated by the reception of an ammunition body 100 can be safely absorbed.

To prevent the guide elements 7.6 from tilting, all four threaded spindles 7.21, 7.22 must be rotated in the same direction at approximately the same speed. Each linear guide 7.2 has a lifting motor 7.23 for this, which is connected via a gearing mechanism 7.24 to the two threaded spindles 7.21, 7.22, so that the two threaded spindles 7.21, 7.22 accordingly rotate synchronously. The respective lifting motors 7.23 of the two linear drives 7.2 are also controlled simultaneously, so that there is a synchronous rotational movement of all four threaded spindles 7.21, 7.22.

Although the receiving tray 7.1 cannot be moved directly in the vertical direction by means of the linear drives 7.2, the receiving tray 7.1 is coupled to the holding device 4 or to the linear guide 7.3. The coupling depends on the position or storage level 2.1, 2.2, 2.3 of the magazine 1 in which the holding device 4 is located. If the holding device 4 is in or above a limit level 2.2, the receiving tray 7.1 is coupled to the holding device 4 and can be moved together with it in a vertical direction. However, if the holding device 4 has been moved below the limit level 2.2, the coupling is released and the holding device 4 is then movable independently of the receiving tray 7.1. In the exemplary embodiment, the middle storage level 2.2 is the limit level 2.2, so that below this level the holding device 4 can be moved independently and thus also relative to the receiving tray 7.1, and above the middle storage level 2.2 the receiving tray 7.1 is movable together with the holding device 4. This is explained in more detail below on the basis of the different positions in FIG. 13.

FIG. 13a first shows the ammunition loading position M, in which an ammunition body 100 can be pushed into the magazine 1 or pushed onto the receiving tray 7.1. The receiving tray 7.1 is located in the middle storage level 2.2 and the holding device in the upper storage level 2.3.

In a next step, the holding device 4 is then transferred from the retaining position H to the transfer position Ü, as can be seen in FIG. 13c. The holding device 4 is then lowered by turning the threaded spindles 7.21, 7.22. During this movement, the receiving tray 7.1 also moves accordingly until it has reached the lower storage level 2.1.

The receiving tray 7.1 is guided by a linear guide 7.3 in the guide element 7.6. At the upper end of the linear guide 7.3, stops 7.4 are provided which ensure that the receiving

tray 7.1 is suspended on the holding device 4 or on the guide element 7.6 if the receiving tray 7.1 is above the lowest storage level 2.1. FIGS. 11 and 12 also show that the receiving tray 7.1 is suspended below the holding device 4 and moves with it.

The distance of the receiving tray 7.1 from the holding device 4 corresponds for the position according to FIGS. 13a to 13d to the distance of the different storage levels 2.1, 2.2, 2.3. If the receiving tray 7.1 has reached the lowest storage level 2.1, this cannot be lowered further, so that then the holding device 4 moves towards the receiving tray 7.1 during further lowering and the movements are no longer coupled. The guide element 7.6 then slides down the linear guides 7.3 of the receiving tray 7.1 during this movement. Due to the common rotation of the two retaining shells 4.2, 4.3 of the holding device 4 by the rotary drive 4.8, the two retaining shells 4.2, 4.3 can be rotated into a grabbing position G, in which the retaining shells 4.2, 4.3 grab an ammunition body 100 from above or rest on top of it from above, as shown in FIG. 13e. The grabbing position G basically corresponds to a 90-degree rotated transfer position Ü, as can also be seen when comparing FIG. 13c and the left illustration of FIG. 14.

In a next step, the holding device 4 is then moved to the retaining position H and the ammunition body 100 is grabbed by the two retaining shells 4.2, 4.3 of the holding device 4 in the manner of a grabber, so that this is then accommodated between the retaining shells 4.2, 4.3 or in the retaining region 4.10 in a form-fitting manner.

If the threaded spindles 7.21, 7.22 are then rotated in the opposite direction and the holding device 4 moves upwards again, the ammunition body 100 is lifted off the receiving tray 7.1 in a vertical direction. This can be seen in FIG. 13g. The holding device 4 can then be moved to the storage level 2.1, 2.2, 2.3 in which the ammunition body 100 is to be stored. The guide element 7.6 then slides upwards again on the linear guide 7.3 until the end of the linear guide 7.3 is reached and the stops 7.4 prevent further relative movement between the holding device 4 and the receiving tray 7.1. If the holding device 4 is then moved even further upwards, the stops 7.4 ensure that the receiving tray 7.1 is moved with it so that the holding device 4 and the receiving tray 7.1 then move upwards uniformly at a distance from a storage level 2.1, 2.2, 2.3.

In FIGS. 13h and 13i, the holding device 4 has grabbed an ammunition body 100, has lifted it off from the receiving tray 7.1 and was then moved to the second storage level 2.2. If the acquired ammunition body 100 is now to be stored in the second storage level 2.2, the two retaining shells 4.2, 4.3 are moved to the transfer position Ü and rotated together around the rotation axis D by the rotary drive 4.8 until the position shown in FIG. 13h is reached. In this position, the ammunition body 100 can then be ejected from the holding device 4 and fed to the conveying device 5, which then transports the ammunition body 100 to the first holding device 4 of the corresponding storage level 2.2. Due to the rotating of the two retaining shells 4.2, 4.3, it is achieved that the ammunition body 100 can be ejected from the holding device 4 not only to the right, but also to the left. For this purpose, the retaining shells 4.2, 4.3 would have to be rotated from the position shown in FIG. 13h in the opposite direction around the rotation axis D until the retaining shells 4.2, 4.3 are on the other side of the ammunition body 100. Theoretically, it would also be possible to rotate the retaining shells 4.2, 4.3 together by 180 degrees around the rotation axis D in order to eject the ammunition body 100 to

the other side. Then, however, the smaller retaining shell 4.2 would be below the larger retaining shell 4.3, which could lead to stability problems.

In order for the holding device 4 or the two retaining shells 4.2, 4.3 to be rotatable in the manner described above and so that the retaining shells 4.2, 4.3 in the projectile lift 7 can be rotated into the retaining position H, the grabbing position G and the transfer position Ü, it is necessary to rotate the retaining shells 4.2, 4.3 relative to the guide elements 7.6. The retaining shells 4.2, 4.3 are rotatably supported in the guide elements 7.6 for this purpose, so that the two retaining shells 4.2, 4.3 can be rotated by the retaining shell drive 4.4 from the retaining position H to the transfer position Ü and by the rotary drive 4.8 from the transfer position Ü to the grabbing position G. Since the gearbox 4.5 and the retaining shell drive 4.4 also rotate around the rotation axis D during the joint rotation of the two retaining shells 4.2, 4.3 around the rotation axis D, these are also accordingly rotatably supported on the guide element 7.6. The rotary drive 4.8 is not rotatable relative to the guide element 7.6, so that it can be firmly connected to the guide element 7.6.

In order to remove an ammunition body 100 from the magazine 1, it must first be fed from the corresponding storage level 2.1, 2.2, 2.3 to the projectile lift 7, then deposited on the receiving tray 7.1 and then moved to the removal position P. In the case of the magazine 1 shown in the figures, both the ammunition loading position M and the removal position E of the receiving tray 7.1 or the ammunition body 100 are located in the middle storage level 2.2. In order to place the ammunition body 100 on the receiving tray 7.1, the holding device 4 retaining the ammunition body 100 must first be moved to the lowest storage level 2.1. Then the retaining shells 4.2, 4.3 are rotated around the rotation axis D into the grabbing position G, as shown in FIG. 13e. In a next step, the holding device 4 is then moved upwards in this grabbing position G without the ammunition body 100. The ammunition body 100 remains on the receiving tray 7.1. In order to convey the ammunition body 100 to the second storage level 2.2, in which it can be pushed out of the receiving tray 7.1 and then fed to the weapon, the holding device 4 must be moved to the highest storage level 2.3. This can be seen, for example, in FIG. 12. The ammunition body 100 can then be pushed out of the receiving tray 7.1 in this removal position E, for example by a thrust element which is not shown in the illustrations.

Furthermore, it is not absolutely necessary to store the ammunition bodies 100 in the magazine 1 from the ammunition loading position M, in which the ammunition bodies 100 are on the receiving tray 7.1, but since the receiving tray 7.1 is open at both ends, the ammunition bodies 100 can also be directly pushed out of the receiving tray 7.1 again and then fed to the weapon. In this respect, the removal position E of the projectile lift 7 also corresponds exactly to that of the ammunition loading position M.

In FIG. 12 it can also be seen that the receiving tray 7.1 has two rectangular recesses 7.11. The two projectile supports 7.5 may extend through these recesses 7.11 when the receiving tray 7.1 is located in the lowest storage level 2.1. Since the ammunition bodies 100 are narrower in the front part than in the rear part, the projectile supports 7.5 serve to support in particular this narrower front part, since the ammunition bodies 100 in this region cannot rest fully on the cylindrical receiving tray 7.1.

The invention claimed is:

1. A projectile lift for the vertical movement of ammunition bodies between two storage levels in a magazine having a receiving tray for receiving an ammunition body and a holding device for holding the ammunition body,
wherein
the holding device can raise the ammunition body vertically from the receiving tray.
2. A projectile lift according to claim 1, wherein the ammunition bodies can be displaced on the receiving tray in the longitudinal direction.
3. A projectile lift according to claim 1, wherein the holding device can be moved relatively in respect of the receiving tray in the vertical direction.
4. A projectile lift according to claim 1, wherein the holding device can raise the ammunition bodies from the receiving tray in the manner of a grab and deposit them on the receiving tray.
5. A projectile lift according to claim 1, wherein the holding device can be moved in the vertical direction via a linear drive.
6. A projectile lift according to claim 5, wherein the linear drive has at least one rotatable threaded spindle which moves the holding device in a vertical direction when rotated.

7. A projectile lift according to claim 5, wherein the linear drive has a guide element which is arranged in the manner of a spindle nut on the threaded spindle.

8. A projectile lift according to claim 6, further including 5 a lifting motor which can drive the threaded spindle of a linear drive via a gearing mechanism.

9. A projectile lift according to claim 1, wherein the receiving tray can be moved in the vertical direction.

10. A projectile lift according to claim 1, wherein the receiving tray and the holding device are coupled to one another in such a manner that the receiving tray can be moved along with the holding device, when the holding device is located within or above a limit level.

15. A projectile lift according to claim 10, wherein the receiving tray is uncoupled from the holding device when said holding device is located below the limit level.

12. A projectile lift according to claim 1, wherein the receiving tray is coupled to the holding device via a linear 20 guide.

13. A projectile lift according to claim 12, wherein the linear guide has a limit stop which limits a movement of the holding device in respect of the receiving tray.

14. A magazine having a projectile lift according to claim 25 1.

15. A method for the vertical movement of ammunition bodies between two storage levels of a magazine having a receiving tray for receiving an ammunition body and a holding device for holding the ammunition body,
30 wherein

the holding device raises an ammunition body vertically from the receiving tray.
